SHARPENER FOR CLOTH CUTTING MACHINES

John B. Gury, Jr., Richmond Heights, Mo.

Application August 31, 1939, Serial No. 292,814

5 Claims. (Cl. 51—249)

This invention relates to sharpeners for blades in cloth cutting machines.

An object of this invention is to provide such a sharpener as an attachment, which will be simple in construction and satisfactory in operation. In my co-pending joint application, Serial No. 259,566, filed March 3, 1939, I have described and illustrated such a sharpener. One of the objects of this invention is to improve the mechanism of the type described in said application by simplifying the parts and mechanism and making other changes to increase efficiency. Specifically, an object of the invention is to provide improved means for securing contact between the grinding wheels and the knife and for securing or permitting rotation of the wheels; to provide non-abrasive stops on cooperating grinding wheels; to provide improved means for rotatively adjusting a block carrying the grinding wheels; to provide improved means for pivotally mounting on the block the spindles carrying the grinding wheels; and to provide improved means for moving the wheels into and out of grinding position.

Other objects will be apparent from the following detail description, taken in connection with the accompanying drawings.

Fig. 1 is an end elevation showing a sharpener assembly with an end plate and a pressure foot of a cloth cutting machine;

Fig. 2 is a front elevation showing a detail;

Fig. 3 is a side elevation;

Fig. 4 is a rear elevation, with sharpener wheels in extended or inoperative position;

Fig. 5 is a view similar to Fig. 4 with the sharpener wheels in operative or sharpening position;

Fig. 6 is a detail partly in section showing a grinding wheel and its method of support;

Fig. 7 is a detail partly in section showing mechanism for rotatively adjusting a block which carries the wheels;

Fig. 8 is an elevation showing the front face of a support;

Fig. 9 is an elevation showing the rear face of the support;

Fig. 10 is an elevation showing a block and grinding wheel assembly; and

Fig. 11 is an exploded view showing separately the parts comprising the assembly illustrated in Fig. 10.

The attachment embodying this invention is made for a cloth cutting machine of commercial construction, which has a base to which is attached a pedestal supporting a motor and other mechanism, to reciprocate a vertical knife 4. In

such a machine a cover plate 5 includes means for slidably supporting a pressure foot bar.

The cover plate 5 includes a block or base 6 which has a vertical slot to accommodate a bar 7 carrying a pressure foot 8 at its lower end. The slot in the base 6 is covered by a plate 9. The bar 7 has at one side a rack or serrations 10, which is engaged by a pawl 11, having teeth at its inner end. The bar is movable horizontally into and out of engaging position by a lever having a bifurcated end or fork (not shown) engaging about a depending pin 13 on the pawl 11. It may be understood that upon release of the pawl 11 by moving it to the left, Fig. 1, through the medium of the lever engaging the depending pin 13, the pressure foot bar 7 with the pressure foot 8 may be raised or lowered. A knob 14 provides means for grasping the bar so that it may be raised or lowered when the pawl 11 has been released.

The sharpener assembly is adapted to slide up and down the lower portion of the bar 7, carrying abrasive wheels 16 and 17. When the sharpener is not in use the abrasive or grinding wheels may be swung away from the blade by means of mechanism which will be later described in detail, and the whole assembly may be secured in an extreme upper position adjacent the block 6 or the cover plate 9. The sharpener assembly has a front plate 18 spaced forwardly from the bar 7 and adapted when the assembly is in uppermost position to lie against the front face of the plate 9 with its upper edge engaging the lower edge of a stop 19 (see Fig. 2). The plate 18 has an open vertical slot 20 at its upper end to accommodate a stud 21 secured to the plate 9 and threaded to receive a nut 22, which when tightened engages the plate 18 and holds the sharpener assembly in its uppermost position adjacent the block 6.

A knob 23 is secured to and extends outwardly from the plate 18, by which the assembly may be moved along the bar 7.

So much of the mechanism as has been described in detail is substantially the same as that illustrated in my joint application, and the same reference numerals have been used to identify like or identical parts in the two constructions.

The sharpener assembly includes a sliding support 60, rigid with the plate 18, a block 61 pivotally mounted for attachment on the support 60 and the grinding wheels 16 and 17 having spindles 62 and 63, supported by brackets 64 which are hinged to the block 61. The support 60 and

the plate 18 are secured together by dowel pins 65 and screws 66. The support has a vertical slot 67 to accommodate the bar 7.

The grinding wheels 16 and 17 are so mounted by brackets 64 on the block 61 that they may be turned into and out of engaging position. They are also mounted in such a manner as to accomplish another object of the invention; that of mounting them in a slanting position so that by rotating the block 61 the assembly may be accommodated to a knife 4 of varying width. They are also mounted so that discs 68 secured to the wheels may engage each other.

The hinged connection between the block 61 and the wheel assemblies may now be described. The wheels 16 and 17 with the discs 68 are rigidly secured to the hubs 69, by nuts 70, as best shown in Fig. 6. Each of the hubs 69 is mounted on a spindle 62 or 63 which is secured to and supported by a bracket 64.

The brackets 64 have hinged connections with the block 61. The block is of I-form with hinge pins 72 and 73 rigid with the brackets and passing through the horizontal arms of the block.

It may now be understood that the wheels will be swung aside, as shown in Fig. 4, during the cutting operation of the machine and will be moved to engaging or grinding position, as shown in Figs. 3 and 5, only when the sharpener is to be used. Convenient means for accomplishing this movement of the wheels into and out of grinding position is accomplished by novel mechanism.

A long arm or crank 74 is rigidly secured to the lower end of one of the hinge pins 73. The outer end of the arm is arranged and adapted to be grasped manually so that the pertinent wheel assembly may be readily turned by grasping and moving the lever 74. The upper ends of the hinge pin 72 have meshing gears 75 rigidly secured to them. Thus when one wheel assembly (carrying the wheel 16) is moved by the lever 74, this movement will be transmitted to the other wheel assembly (carrying the wheel 17) so that both wheel assemblies will be moved in unison into and out of grinding position.

To secure tension, a short crank 76 is secured to the lower end of the hinge pin 73 which is pertinent to the assembly of the wheel 17 and a spring 77 connects the two cranks 74 and 76. The spring is so mounted with respect to the cranks 74 and 76 as to exert tension to hold the wheel assemblies either in operative position, as shown in Fig. 5, or in inoperative position, as shown in Fig. 4. The spring also exerts tension to yieldingly hold the wheels against the blade when sharpening.

The discs 68 act as stops to limit the movement of the wheel assemblies with reference to each other and prevents the abrasive cylinders of the wheels from contacting each other, in which case excessive wear would result. Experience has shown that the discs wear less by contact with each other than the cylinders do from contact with the knife.

Rotation of the wheels is brought about by their contact with the reciprocating knife. The block 61 is rotated on its pivot 78 just sufficiently to cause the wheels to bear with a slight tension (under the influence of the spring 77) against the blade and to separate the discs 68 from each other. With this arrangement, ideal sharpening conditions are provided and the wheels turn freely without any uneven wearing of their periphery. Any high points on the cylinders tend to wear away immediately.

While the hinge pins 72 and 73 are parallel and lie in a vertical plane, the wheels 16 and 17 and their spindles 62 and 63 are slanting. The wheel 16 slants downwardly and the wheel 17 slants upwardly. That is, the wheels are supported with their axis oppositely positioned at an acute angle to a horizontal plane. Then by turning the block 61 the assembly may be adapted for a knife with a narrower blade. Thus, with the block in a vertical position or almost vertical position, as shown in Figs. 4 and 5, the wheels will be adapted to grind a knife of extreme width, but by rotating the block 61 in a clockwise direction, Figs. 4 and 5, the assembly will be adjusted for a knife of lesser width.

Novel means are provided for rotatively adjusting the block 61. The block 61 is pivotally mounted on a horizontal stud 78 rigidly secured to the support 60. A screw 79 on the end of the shaft 78 holds the block 61 in assembly with the support 60. Means for turning the block 61 about the stud 78 on its support 60 are illustrated in detail in Fig. 7. A bracket 80, which includes a collar, is loosely mounted by a pin 81 on the support 60, to which it is secured by a screw 82. A nut 83 is mounted in the collar of the bracket 80 and has secured to it a thimble 84 by which the nut may be turned. A screw 85 is threaded in the nut 83 and has a crosshead 86 with a pin 87 engaging in a hole 88 in the front or inner face of the block 61. Thus by turning the thimble 84 the screw 85 may be moved to adjustably rotate the block 61.

A guard 89 is attached to the outer end of the shaft 62, which guard is placed to engage a part of the machine assembly, not illustrated in the drawings, to prevent the grinding wheels from coming in contact with and abrading the frame of the machine.

From the foregoing description it will be seen that the invention accomplishes its objects. Improved and simplified means have been provided for mounting grinding wheels on an assembly for sharpening blades of cloth cutting machines. Simple means have been provided for securing tension between the wheels and between the wheels and the knife, permitting the wheels to rotate freely while grinding. Simplified means have been provided for moving the wheels in unison into and out of grinding position. Simple means have also been provided for mounting the wheels in a slant position, so that by rotating the block to which they are hinged the mechanism can be adjusted to grind wide or narrow blades.

Various changes may be made in the details of construction within the scope of the appended claims, parts of the invention may be used without the whole, and various additions or improvements may be made while retaining the advantages of this invention. This invention has been described in part as an improvement upon a device illustrated, described and claimed in a pending joint application for patent, but it will be understood that, except as the appended claims require, it is not essential that this invention be used with the specific mechanism or devices therein described.

I claim:

1. In a sharpener attachment for a reciprocating vertical blade in a cloth cutting machine, the improvement comprising a support, a pair of abrasive wheels, a block mounted for rotative adjustment on the support, a pair of brackets, parallel hinge pins secured to the brackets and pivotally connecting the brackets with the block,

inter-meshing gears secured to the pins, and spindles supporting the wheels on the brackets respectively, said spindles being so supported in their respective brackets as to be oppositely slanted from a horizontal plane.

5 2. In a sharpener attachment for a reciprocating vertical blade in a cloth cutting machine, the improvement comprising a support, a pair of abrasive wheels adapted to simultaneously contact the blade on their periphery, a block mounted for rotative adjustment on the support, a pair of brackets, parallel hinge pins connecting the brackets with the block, and spindles for the wheels supported by the brackets at oppositely disposed angles from the horizontal.

10 3. In a sharpener attachment for a blade in a cloth cutting machine, the improvement comprising a pair of abrasive wheels, a block, a pair of brackets supporting spindles for the wheels, hinge pins connecting the brackets to the block whereby the wheels may be swung into and out 15 of grinding position, and non-abrasive circular discs secured to the wheels respectively and

adapted to contact each other on their peripheries.

4. In a sharpener attachment for a blade in a cloth cutting machine, the improvement comprising a pair of abrasive wheels, a block, a pair of brackets supporting spindles for the wheels, hinge pins connecting the brackets to the block, hubs on the spindles, non-abrasive circular discs on the hubs adapted to contact each other on their peripheries, and means for clamping the 5 wheels and the discs to the hubs.

10 5. In a sharpener attachment for a blade on a cloth cutting machine, the improvement comprising a support, a block pivoted on said support, abrasive wheels carried by said block, a bracket on the support having a collar, a manually engageable nut mounted in the collar, a screw threaded in the nut, and means for connecting the screw and the block, whereby rotation of the nut will adjust the block on the support.
